UNITED STATES PATENT OFFICE.

CHARLES C. BEAM, OF CUMBERLAND, MARYLAND, ASSIGNOR TO THE POTOMAC GLASS COMPANY, OF CUMBERLAND, MARYLAND, A CORPORATION OF MARYLAND.

DESIGN FOR A CANDLE HOLDER OR SIMILAR ARTICLE.

Application filed January 12, 1928. Serial No. 24,834. Term of patent 3½ years.

To all whom it may concern:

Be it known that I, CHARLES C. BEAM, a citizen of the United States, residing at Cumberland, in the county of Allegany and State of Maryland, have invented a new, original, and ornamental Design for a Candle Holder or Similar Article, of which the following is a specification, reference being had to the accompanying drawing, forming part thereof.

The figure is a perspective of a candle holder or similar article showing my new design.

I claim:

The ornamental design for a candle holder or similar article as shown.

CHARLES C. BEAM.
